ASSIGNORS TO UNION BED AND SPRING COMPANY, OF CHICAGO, ILLINOIS, A COR-
PORATION OF ILLINOIS

BEDSPRING

Application filed September 12, 1929. Serial No. 392,028.

Our invention pertains to spring structures, such as bed-springs, furniture-springs, seat and back cushions, etc., but its preferred embodiment and perhaps its most valuable use is in connection with bed-springs, although the principles of construction employed may be advantageously availed of in other structures.

In general, the invention concerns more particularly the employment of a supplemental, inner, border wire used in conjunction or association with the customary marginal wire extending around the upper edge of the bed-spring, and it relates also to the use of short, helical springs operating in conjunction with the upright, spiral-springs to yieldingly maintain the latter in correct vertical relation with capacity for suitable yielding action, whereby to supply the spring structure with those desirable cushioning qualities sought after with unlikelihood of any of the spring parts becoming displaced so that they could not properly perform their intended functions to best advantage.

To enable those acquainted with this art to fully understand the invention from structural and functional or operating standpoints, in the accompanying drawing, forming a part of this specification, a present, preferred or desirable embodiment of the invention has been illustrated in detail, and, for the sake of simplicity, like parts, throughout the several views, have been designated by the same reference numerals.

In this drawing:

Figure 1 is a fragmentary plan view of a corner portion only of the bed-spring;

Figure 2 is a vertical section on line 2—2 of Figure 1; and

Figure 3 is a similar vertical section on line 3—3 of Figure 1.

Referring to this drawing, it will be observed that the bed-spring comprises a rectangular, marginal, frame angle-bar 10, supporting a plurality of spaced, parallel straps 11 on which, in any approved manner, as by tie-wires 12, are mounted the lower ends of a corresponding number of rows of upright, spiral-springs 13, 13, shorter vertically-dis-

posed spiral-springs 14, 14 being arranged around the outer side of the bed-spring structure and suitably supported on the frame, the top coils or convolutions of all such springs being yieldingly joined or connected together by intersecting or crossing helical springs 15, 15.

A border-wire 16, of substantial cross-section, extends around the upper rim or edge of the bed-spring along or just above the top convolutions of the spiral-springs 14, 14, arranged around the margin of the structure, such rim wire 16, being secured to the tops of the associated spiral-springs by wires 17 bent at 18, 18 to wrap around and fasten together the border wire referred to and the spring coils as is clearly illustrated, each such securing wire extending along the full length of the side of the bed-spring on which it is used with straight sections 19, 19 between its spaced, bent, fastening or securing portions 18, 18.

An inner, rectangular, supplemental or auxiliary border-wire 21, spaced inwardly away from the complementary or companion wire 16, is also employed above the top coils of the same marginal, upright, spiral-springs 14, and such wire 21 along the lengthwise dimension of the bed-spring is tied or attached to two adjacent or adjoining springs 14, by short wires 22, each bent at its ends at 23, 23 to form the securing means.

Thus the outer row of upright spiral-springs is equipped with two wires 16 and 21 overlying and fastened to them, hence maintaining the proper substantially-vertical disposition of the springs under all conditions of service, a situation not likely to be preserved where only a single outer border-wire is used as has heretofore been customary.

Furthermore, since such outer row of springs is thus more securely tied together, stronger, helical springs 15 may be availed of, if desired, because there is no substantial danger to such horizontal springs bowing the border-wires inwardly.

Hence the use of the additional or complementary, inner, border-wire and its fastening to the outer row of spiral-springs permits a desirable employment of connecting-helical springs of greater strength than has hereto-

fore been customary, and, accordingly, the upper or top coils of the springs are more efficiently yieldingly united together without danger of detrimental displacement from the correct vertical arrangement.

Another feature of the invention resides in tying such upright springs flexibly together at an intermediate point in their heights and in such a way to assist materially in the preservation of their vertical order without interfering with their faultless compression in the performance of their cushioning office.

To this end, each spring 13, substantially midway its height, is provided with adjacent or contiguous substantially-parallel coils 24, 24, closer together than its other convolutions, which slidingly accommodate between them a pair of crossed wire-clips 25, 25 centrally bent or deformed to extend over one another and with loops or eyes 26, 26 at their opposite ends just outside of the spring convolutions between which they fit.

As is clearly presented in the drawing, such clip eyes are connected by horizontal, helical springs 27, 27 to the complementary attachment eyes of the like clips of the springs next adjacent thereto, whereby each such upright, spiral-spring is yieldingly connected at about halfway its height with four other springs, each of which in turn is in like manner flexibly joined to its neighbors.

Thus the intermediate sections of the vertical, main, supporting springs are yieldingly held in place, but, nevertheless, in such manner, that they can flex and shift adequately to afford the spring structure, as a whole, desirable resilient properties and without direct attachment of the helical-springs to the spiral-springs.

Along the border of the bed-spring, the intermediate helical-springs 28 are connected at their outer ends to the angle-bar 10 of the framework as is indicated in Figures 2 and 3.

From the foregoing, it will be apparent that the supplemental or inner border-wire materially aids in keeping the upright disposition of the marginal spiral-springs even though they may be only locally depressed in material degree, with the result that such springs, because of their union with their companions, in the manner specified, are prevented from tilting or tipping out of place. At least they are precluded from permanently becoming mal-positioned even though subjected to unusual and severe strains.

It will be observed that there is a direct cooperation between the use of the inner border-wire in the manner specified and the way in which the springs are tied together horizontally about midway between their tops and bottoms, the two features of construction conjointly resulting in a bed-spring having the qualities and properties above set forth.

Although only one embodiment of the in-

vention has herein been presented, it will be understood by those skilled in this art that many minor mechanical changes may be incorporated in the construction thus illustrated and described in detail without departure from the heart and essence of the invention and without the sacrifice or loss of any of its substantial benefits or advantages.

We claim:

In a bed-spring, the combination of a supporting-frame, a plurality of upright spiral-springs mounted on said frame and arranged in rows, an outer border-wire, means securing said outer border-wire to the extreme outer portions of the top convolutions of the marginal spiral-springs, an inner border-wire crossing said convolutions of said border springs at a distance from their innermost portions, means securing said inner border-wire to said convolutions at their points of crossing, said three connections of said border-wires with each top convolution except those of the corner springs, being roughly equally spaced apart to secure effective stiffening of the structure, and helical-springs connecting the top convolutions of said upright springs together, each of said border springs, with the exception of the corner ones, having its top convolution connected by two of such helical springs to two upright springs in the next rows on opposite sides of the row of which the spring under consideration forms a part.

In witness whereof we have hereunto set our hands.

GEORGE G. POWERS.
LAWRENCE J. SIEGER.
